[57] CLAIM

The ornamental design for an adjustable electrical cord clamp, substantially as shown.

DESCRIPTION

FIG. 1 is a perspective view of an adjustable electrical cord clamp showing our new design;

FIG. 2 is a top plan view;

FIG. 3 is a side elevational view taken from the right of FIG. 1;

FIG. 4 is a side elevational view taken from the left of FIG. 1;

FIG. 5 is an end elevational view taken from the left of FIG. 3;

FIG. 6 is an end elevational view taken from the right of FIG. 3; and

FIG. 7 is a bottom plan view.
